UNITED STATES PATENT OFFICE.

CHRISTIAN WILDHABER, OF NEW YORK, N. Y.

DEVICE FOR SEPARATING PINS FROM SWEEPINGS.

Application filed April 9, 1926. Serial No. 100,893.

The present invention relates to improvements in devices for separating pins and needles from the sweepings of tailoring and clothing-producing establishments, and has 5 for its main object to produce a simple and comparatively inexpensive separating apparatus, whereby the sweepings are with little labor and conveniently assorted, and dust and other foreign matter separated therefrom.

Another object of the invention is to construct a device which separates the bent and other pins not fitted for use from the salable articles.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claims, without departing from the spirit or sacrificing any of the advantages of the invention.

One of the many possible embodiments of 30 the invention is illustrated in the accompanying drawings, in which:—

Figure 1 is a side elevation of a separating apparatus constructed in accordance with the present invention; Fig. 2 is a section taken on line 2—2 of Fig. 1; and Fig. 3 is a section taken on line 3—3 of Fig. 2.

In the drawings, the numeral 11 indicates the side members of a frame, which are connected by transverse tie rods 12, or otherwise. On these side frame members are formed bearings 13, in which is rotatably journaled a horizontally extending transverse shaft 14, to which is fixed a drum 15. The heads 16 of this drum are 45 imperforate, while the cylindrical wall 17 thereof is made of some foraminated material, for instance wire fabric. A portion of the cylindrical wall of the drum, denoted by the numeral 18 (Fig. 3), is detachable, to permit of access to the drum, into which the sweepings are placed. The portion 18 forms thus a cover, which may be held in position upon the drum proper by any suitable locking means, denoted in 50 the drawings by the numeral 19. On the interior of the drum are formed radially

extending baffles 20, which have a tendency to carry the sweepings in the drum upwards. The drum is disposed within a casing 21, part of the side walls of which 60 is formed by the frame members 11. The bottom 22 of this casing is slanting as clearly shown in Figs. 1 and 3 of the drawings and provided with an outlet opening 23, that extends from side to side 65 of the casing. The top portion 24 of the casing is in the form of a cover, that is hinged at 25 to the side frame members 11. By lifting this cover, access may be had to the drum of the separating 70 device. The casing is provided with a nipple 26, to which may be attached the suction pipe of an air pump, which, when in operation, removes from the casing dust and small material, as the same is separated from the 75 sweepings and moves through the foramina in the cylindrical wall of the drum toward the outlet opening 23 of the casing.

The pins, which are separated in a manner hereinafter to be described from the 80 sweepings in the drum 15, slide down the inclined bottom of the casing 21 and are discharged through the outlet opening 23 onto a belt conveyer 28, comprising two rollers indicated at 29 and 30, which are 85 rotatably mounted in a frame 31, including two side members 32 connected by tie rods 33. Over these rollers runs a plurality of belts 34, separated by vertical slats 35, which project above the belts. The slats 90 are attached to a plate member 36, which is supported by transverse strips 37. These strips are secured to the side members 32. The distance between each two adjacent slats 35 is a few times larger than the diameter of the head of an individual pin, but smaller than the length of a pin. The 95 acting portion of the belt conveyer is inclined forwardly, as clearly appears from Figs. 1 and 3 of the drawings, and the free edges 35' of the slats 35 slant also forwardly, their front edges 39 projecting a considerable distance in front of the roller 30.

In front of the belts 34 is placed a board 40, which slants from the roller 30 downwards, there being a gap between the last-mentioned roller and the said board. Below this gap is provided an inclined board 41, and in front of the front edges 39 of the slats 35 an inclined board 42. The boards 100 40, 41 and 42 are mounted on the frame 31. The drum and conveyer are actuated from 105 110

any suitable source of power, driving a belt 43, which runs over a pulley 44 on a driving shaft 45, the latter being journaled in a bearing 46 on one of the side frame members 11. To the same shaft is fixed a gear 47, in mesh with a gear 48, keyed to the drum shaft 14. The gear 47 meshes also with a gear 50' on a counter shaft 49, journaled in one of the frame members 11, the gear 50' meshing with a gear 50, which is fixed to the shaft 51 of the conveyer roller 29.

In order to permit the drum to be removed from the device, the bearings 13 thereof are each made of two sections, one section 13 of each bearing, denoted by the numeral 13', being adapted to be disengaged from the other section, whereby, upon opening the cover 24 of the casing 21, the drum with the gear 48 thereon may be removed from the device. The frame 31, with the elements mounted thereon, is also removable as a unit, from the side frame members 11. This becomes necessary in case one of the belts 34 is torn and is to be replaced. In order to permit the frame 31 to be removed, each of the side frame members 11 is provided with a slot 52, through which the shaft 51 may be inserted.

The operation of this device is as follows: The sweepings are placed into the drum 15. After the cover 24 of the casing 21 has been placed to closing position, the driving shaft 45 is actuated. The drum is thus rotated, the baffles 20 therein carrying the sweepings continuously upwards, they dropping, when they reach in their upward travel a certain level, back to the lowermost point of the drum. While being thus carried upwards and dropping back to the lowermost point of the drum, dust and other like particles are separated from the sweepings by the air pump, and carried away through the nipple 26. Such dust and other like particles, which find their way through the foramina in the drum onto the slanting bottom 22 of the casing 21, are also removed by the air pump.

Pins and needles pass through the foraminated cylindrical wall of the drum, the mesh of the screen of which is larger than the head of a pin. The pins and needles slide down the inclined bottom 22 of the casing 21 and pass through the outlet opening 23 in the said bottom onto the conveyer 28. On this conveyer the pins are caused to travel lengthwise, that is to say with their longitudinal axes arranged parallel or substantially parallel to the direction of travel,

for the reason that the slats 35 are disposed at a distance from each other which is smaller than the length of a pin. Such pins which are bent cannot drop onto the conveyer belts, but slide down on the slats 35. The perfect pins move over the gap between the conveyer belts and the board 40 onto the said board, and slide down the board into a receptacle, not shown. The bent pins, on the other hand, and all such other material which is of a size larger than the distance between adjacent slats 35 slide down on the 70 said slats on the board 42 and thence into a second receptacle, not shown. Such material separated from the sweepings which is smaller than the distance between adjacent slats moves on the conveyer belts downwards, but not onto the board 40, falling through the gap between the conveyer belts and the board 40 onto the board 41, and drops into a third receptacle, not shown. In this manner the perfect pins and needles are 80 separated from those which cannot be used again commercially.

After the sweepings have been treated for sometime in the manner indicated, the apparatus is stopped and the material removed 85 from the drum to be assorted either by hand or on another machine.

What I claim is:—

1. A pin assorting device including an inclined belt conveyer, longitudinally extending parallel slats dividing the acting portion of said conveyer, the distance between adjacent slats being smaller than the length of a pin, a slanting board adjacent the discharge end of said conveyer, said slats projecting forwardly of said conveyer, and a slanting board adjacent the forwardly extending ends of said slats.

2. A pin assorting device including an inclined belt conveyer, longitudinally extending parallel slats dividing the acting portion of said conveyer, the distance between adjacent slats being smaller than the length of a pin, a slanting board adjacent the discharge end of said conveyer, the inner edge 100 of said board being disposed from said conveyer at a distance whereby a gap is formed between said conveyer and said board, said slats projecting forwardly of said conveyer, a slanting board adjacent the forwardly extending ends of said slats, and a slanting board disposed below said gap.

Signed at New York, in the county of New York, and State of New York, this 8th day of April, A. D. 1925.

CHRISTIAN WILDHABER.
